Primary Examiner—Janice E. Seeger[57] **CLAIM**

The ornamental design for a desk for a vehicle steering wheel, as shown and described.

DESCRIPTION

FIG. 1 is a front perspective view of a desk for a vehicle steering wheel showing my new design;
FIG. 2 is a slightly enlarged front elevational view thereof;
FIG. 3 is a slightly enlarged back elevational view thereof;
FIG. 4 is a slightly enlarged bottom and view thereof;
FIG. 5 is a slightly enlarged top end view thereof; and,
FIG. 6 is a slightly enlarged right side view thereof, with the
left side view appearing as a mirror image.
